MELVILLE EASTHAM, OF CAMBRIDGE, MASSACHUSETTS, ASSIGNOR TO GENERAL RADIO COMPANY, A CORPORATION OF MASSACHUSETTS.

APPARATUS FOR PRODUCING ELECTRICAL OSCILLATIONS.

1,194,154.

Specification of Letters Patent.

Patented Aug. 8, 1916.

Application filed December 28, 1914. Serial No. 879,299.

To all whom it may concern:

Be it known that I, MELVILLE EASTHAM, a citizen of the United States, residing at Cambridge, in the county of Middlesex and 5 State of Massachusetts, have invented certain new and useful Improvements in Apparatus for Producing Electrical Oscillations; and I do hereby declare the following to be a full, clear, and exact description of the invention, such as will enable others skilled in the art to which it appertains to make and use the same.

The present invention relates to apparatus for producing electrical oscillations 15 and more particularly to such apparatus for use in wireless signaling.

One feature of the invention relates to the construction and coördination of an oscillatory circuit and an impulse circuit where- 20 by the oscillations are produced by impact excitation. The oscillatory circuit, which is preferably also the radiator circuit, is closely coupled with an exciting or impulse circuit. The impulse circuit includes a con- 25 denser and a discharge gap which is so constructed that, in conjunction with the rapid transfer of energy from the impulse circuit to the oscillatory circuit due to the close coupling between them, it serves to so rapidly 30 quench the discharge that pure impact excitation, or a condition approximating pure impact excitation, is attained. The impulse circuit is not tuned to the oscillatory circuit but preferably has a natural time period 35 considerably in excess of that of the oscillatory circuit.

Another feature of the invention relates to a reservoir circuit which alternately receives and gives up electrical energy during 40 the operation of the apparatus.

Still other features of the invention relate to certain combinations and arrangements of parts hereinafter described and particularly pointed out in the claims, the advantages of which will be apparent to those skilled in the art.

In the drawings, Figure 1 is a diagrammatic view illustrating the preferred embodiment of the apparatus of the present 50 invention, and Figs. 2 and 3 are diagrams indicating the relation between the oscillations in the oscillatory circuit and the exciting impulses in the impulse circuit.

The preferred form of the apparatus illustrated in the drawings first will be described 55 and then its mode of operation pointed out.

The oscillatory circuit, indicated generally by reference numeral 1, is an antenna or radiating circuit, and includes an aerial wire 2 which is grounded at 3. Included in the 60 circuit 1 is an air-core auto-transformer 5. Closely coupled with the oscillatory circuit 1 by means of the auto-transformer 5, is a non-oscillatory exciting or impulse circuit 6. While the necessary close coupling is 65 more easily got by means of the direct coupling of the auto-transformer, nevertheless, a transformer having separate primary and secondary coils might be employed. The impulse circuit is connected as shown, to the 70 auto-transformer so that it acts as a step-up transformer. The impulse circuit 6 is a closed circuit including a discharge gap 7, a condenser 8, and an adjustable inductance 9. During the operation of the apparatus, the 75 condenser 8 is alternately charged from the feeding circuit and discharged through the discharge gap 7. The discharge gap is a rotary sectored gap of the type described in the patent to Eastham No. 1,056,892, March 25, 1913, to which reference may be had for the details of its construction. The discharge gap comprises two copper disks 10 and 11, the opposing faces of which are parallel and are formed with raised sectors. 80 The disk 11 is stationary and the disk 10 is rotated. As the disk 10 is rotated, the raised sectors of each disk alternately coincide with the sectors of the other disk and with the cutaway portions between the sectors. The 85 speed of the disk 10 is such that the raised sectors coincide with some audible frequency, for example five or six hundred coincidences per second. When the raised sectors of the gaps coincide, a succession or 90 group of discharges from the condenser 8 takes place. When the sectors coincide with the cutaway portions of the opposite disk no discharge takes place. The effect of the 95 gap is to cause the sending of oscillations 100 having an audible group frequency. An important feature of the gap and one which adapts it for use in the present apparatus is the effective quenching of the discharge. The two surfaces of the discharge gap are 105 continuously moving with relation to each

other. As a consequence of this, the discharge does not form a localized persistent arc, because the points at which the discharge takes place are continuously being separated by the movement of the surfaces 5 and new and comparatively cool surfaces are presented. The disks are of comparatively heavy plates of copper which is a good heat conductor and the gap is constructed so as 10 to readily radiate heat. The action of the gap in continuously presenting fresh and comparatively cool surfaces for the discharge in conjunction with its ready dissipation of heat, is important in that it permits 15 comparatively large discharge currents to be employed in the impulse circuit so that a comparatively large amount of energy may be radiated from the antenna circuit.

The impulse circuit 6 is not tuned or in 20 resonance with the oscillatory circuit 1. Instead, the impulse circuit 6 has a natural time period considerably greater than that of the oscillatory circuit 1. While it is preferable that the impulse circuit 6 have 25 a natural period of about fifty per cent. greater than that of the oscillatory circuit 1, this is not necessary as the natural period of the impulse circuit 6 may vary from this preferred relation within comparatively 30 wide limits. One of the advantages in having the impulse circuit untuned and out of resonance with the oscillatory circuit 1, resides in the fact that the impulse circuit 6 will not tend to resonate with the oscillatory 35 circuit 1, and, therefore, the tendency of the oscillatory circuit 1 to react and retransfer energy to the impulse circuit is minimized. If the impulse circuit 6 had the same natural time period as the oscillatory circuit 1, a 40 condition of resonance between them would result, and because of this, there would be an undesirable tendency for the impulse circuit 1 to re-transfer energy back to the impulse circuit 6. Because of the untuned relationship between the impulse circuit 6 45 and the oscillatory circuit 1, this undesirable tendency is counteracted. Another advantage in having the impulse circuit 6 out of tune with the oscillatory circuit 1 and of 50 a greater natural time period, resides in the fact that there is produced in the impulse circuit 6 a current impulse or condenser discharge of greater wave length than the current waves in the oscillatory circuit.

This impulse wave has a duration of over 55 one half greater than the duration of a single alternation or half oscillation of the oscillatory current in the oscillatory circuit 1. The impulse wave, therefore, laps over about 60 one and a half or more of the single alternations or half oscillations of the oscillatory current. As hereinafter pointed out, this impulse wave is such as to efficiently transfer energy from the impulse circuit to the 65 oscillatory circuit.

The condenser 8 is charged by means of a feeder circuit 15. The feeder circuit 15 includes a high tension direct current generator 16, having an electromotive force of about two thousand five hundred volts. The 70 feeder circuit 15 includes choke coils 17 between the generator and its connection to the impulse circuit, for preventing the impulse circuit from reacting on the generator. In the feeder circuit is included the sending 75 key 18.

A reservoir circuit 20 is connected to the impulse circuit 6 for the purpose of storing energy during the time that the gap 7 is not discharging and delivering the energy to 80 the impulse circuit when the gap 7 is discharging. The reservoir circuit 20 includes an inductance 21 and a condenser 22. The inductance 21 and the condenser 22 are so proportioned that the reservoir circuit 20 85 has a natural frequency approximating that of the group frequency caused by the rotary gap 7. The electrical dimensions of the circuit 20 are such that the circuit is enabled to absorb practically the full output of the 90 generator 16 during the interval when no discharge takes place across the discharge gap 7. The reservoir circuit 20 thus permits the full output of the generator 16 to be utilized. The tuning of the reservoir 95 circuit 20 to the group frequency of the discharge gap causes the energy to surge in and out of the reservoir circuit 20, the energy surging into the reservoir circuit 20 while the raised sectors of the gap 7 are 100 opposite the cutaway portions and no discharge can take place in the gap 7, and surging out of the reservoir circuit to supplement the current delivered from the generator when the raised sectors of the gap 7 105 coincide and the group of condenser discharges takes place. The condenser 8 can receive energy and transfer it through the impulse circuit to the oscillatory circuit only during those intervals when the sectors 110 of the gaps are in coincidence. The periods of coincidence occur many hundred times per second, so that the current absorbed by the condenser 8 is an intermittent current which is interrupted many hundred times a 115 second. If the condenser 8 were connected directly across the direct current generator without the reservoir circuit 20, it would be necessary for the generator to furnish an interrupted current, each pulsation of which 120 would have a duration of the order of about a thousandth of a second. The direct current generator, of course, has a considerable internal inductance, so that it would be impossible for the generator to build up its full 125 current strength during this brief interval of time. Consequently, without the reservoir circuit, only a fraction of the normal output of the generator would be available.

The operation of the apparatus is as fol-

lows: Assume the sending key 18 is closed and a signal is being sent. The generator 16 continuously supplies energy. During the intervals when the raised sectors of the 5 gaps are opposite the cutaway portions of the opposite plate, no discharge takes place through the discharge gap 7 and the reservoir circuit 20 receives and stores energy. When the sectors of the gap come into coincidence, the condenser 8 is charged, partially directly from the generator 16 and partially from the reservoir circuit 20, and then discharged through the discharge gap 7. The frequency of the discharge across 10 the discharge gap 7 is determined by the length of time consumed for the condenser 8 to become charged to the potential necessary to break down the discharge gap. This time is dependent upon the capacity of the 15 condenser 8 and the rate at which it is supplied with current. This time can be varied by changing the relationship between the capacity of the condenser 8 and the rate at which it is charged. A number of condenser discharges takes place during each 20 coincidence of the sectors of the gap. When the apparatus is adjusted to good working condition, the condenser discharge is non-oscillatory and consists of a substantially 25 uni-directional current impulse or wave. This current impulse begins when the potential across the discharge gap is sufficient to strike an arc and ceases when the potential across the discharge gap drops to a voltage 30 sufficiently low so that the arc is no longer maintained. The impulse circuit 6 is closely coupled with the oscillatory circuit 1, the coefficient of coupling between the circuits being preferably more than fifty per 35 cent. With one form of the apparatus, the most satisfactory results were obtained with a coefficient of coupling of about sixty per cent. This coupling is closer than it has heretofore been the practice to employ in 40 wireless apparatus. This closer coupling is one of the essential factors in attaining impact excitation in the present apparatus. Because of the close coupling, practically all 45 of the energy in the impulse circuit 6 due to the discharge of the condenser is transferred to the oscillatory circuit 1 during a single current wave. This transfer of energy leaves so little electro-magnetic energy in the impulse circuit that the discharge gap 50 is able to then extinguish the arc. The general relation between the condenser discharge and the oscillations in the oscillatory circuit is indicated in Figs. 2 and 3 of the drawings. The current curves in Figs. 2 55 and 3 are plotted from Braun tube oscilograms which were taken in testing the apparatus. The sources of error were such that the current curves are not plotted to exact scale. They do, however, serve to give an insight into the general relation-

ship of the currents. It is to be understood, therefore, that Figs. 2 and 3 are diagrammatic in nature and that they do not purport to illustrate the exact form of the current impulses and oscillations or their exact phase relation, the purpose being to illustrate in an approximate way the relationship of the exciting impulse to the excited oscillation in order to more easily explain the present invention. In Fig. 2 is diagrammatically illustrated the relationship between the condenser discharge and the excited oscillations when the condenser is discharged at such a rate that a succeeding discharge impulse takes place before the previously excited wave train in the oscillatory circuit has died out. In Fig. 3 is diagrammatically indicated the relationship of the condenser discharge and the excited oscillations when the condenser is charged slowly 80 enough so that the previously excited train of waves dies out before the succeeding condenser discharge. 85

In Fig. 2 the heavy lines 30 indicate the current impulse or condenser discharge in 90 the impulse circuit 6 and the light line 31 indicates the oscillatory current in the oscillatory circuit 1. The positive maxima of the oscillatory current are indicated at 32, the negative maxima at 33, and the zero 95 values at 34. The oscillations in the oscillatory circuit are free oscillations and have of course substantially the same period as the natural time period of the oscillatory circuit. It will be noted that the current impulses 100 30 occur in a predetermined phase relationship with the oscillations. This is due to the fact that, as the condenser 8 is being charged from the feeder circuit, the oscillations in the oscillatory circuit 1 react 105 on the impulse circuit 6 to impress ripples of electro-motive force across the discharge gap 7. These ripples of electro-motive force serve to trigger off the condenser discharge 110 30 in the predetermined phase relationship with the oscillations 31 which is indicated approximately in Fig. 2. The impulses 30 occur in such relationship to the oscillations 31 that the condenser discharge impulses 30 reinforce and continue the already existing 115 train of oscillations 31. The effect of the impulse 30 is, therefore, not to appreciably change the phase relationship of the oscillations which succeed it with relation to the oscillations which precede it, but instead, 120 its effect is to reinforce and continue the preceding train of oscillations. Thus a train of continuously sustained oscillations is maintained in the oscillatory circuit, the desirability of which is too well recognized to require comment. When triggering takes place, at least one complete oscillation in the oscillatory circuit intervenes between successive impulses in the impulse circuit, 125 so that the number of oscillations per unit 130

of time is an integral multiple of the number of impulses.

In Fig. 3 the heavy line 40 indicates a current impulse or condenser discharge in the impulse circuit 6, and the light line 41 indicates the excited train of oscillations in the oscillatory circuit 1. The positive maxima of the oscillatory current are indicated at 42, the negative maxima at 43, and the zero values at 44. As shown in Fig. 3, the previously excited train of oscillations has died out before the impulse 40 takes place so that the train of excited oscillations 41 begins with the impulse 40.

15 As shown in both Figs. 2 and 3, the current impulses or condenser discharges indicated at 30 and 40, have a considerably greater duration than the single alternations or half complete oscillations of the oscillatory current. As shown in Fig. 2, the condenser discharge 30 begins, due to the triggering, at a point between a positive maximum 32 and the following zero value 34 of the oscillatory current 31, and continues until about the next succeeding positive maximum 32 of the oscillatory current. Under this condition, the current impulse or condenser discharge 30 has a duration nearly twice that of the single alternations 80 or waves of the oscillatory current 31. As shown in Fig. 3, the excited train of oscillations 41 begins at a zero point 44 which coincides with the beginning of the condenser discharge 40. The oscillations 41, of course, have approximately the natural time period of the oscillatory circuit 1. The current impulse or condenser discharge 40 laps over about one and one-half of the single alternations of the oscillatory current 41, terminating at about the first positive maximum 42. Thus, in this case, the current impulse 40 may be considered to have a wave length about one and one-half times as long as the wave length of the current 45 in the oscillatory circuit.

The expression "alternation" is here used to define the single alternation or current flow which takes place between two succeeding zero values of the oscillatory current. A complete "oscillation" is made up of two "alternations", one alternation being positive and the other being negative.

The shape and duration of the exciting impulse or condenser discharges 30 and 40 55 is important for the transfer of energy from the impulse circuit 6 to the oscillatory circuit 1. The electromotive force exerted by the impulse 30 or 40 on the oscillatory circuit 1 is expressed by the formula

$$60 - M \frac{di_1}{dt}$$

where M is the mutual inductance of the circuits 6 and 1, i_1 is the current impulse 65 in the circuit 6 and t is the time. When the

current i_1 is increasing to a positive maximum, the electromotive force is, of course, negative and when the current i_1 is decreasing to its zero value, the electromotive force is, of course, positive. As will be evident 70 from an examination of the diagrams in Figs. 2 and 3, this electromotive force is in phase with the current in the oscillatory circuit 1 during the greater part of the current impulse in the impulse circuit 6, so 75 that the effect of the current impulse is to transfer energy from the impulse circuit 6 to the oscillatory circuit 1.

Apparently there occurs one or more brief periods during the impulse when the electromotive force is opposite in phase to the current in the oscillatory circuit, but the amount of energy which would be thus transferred back from the oscillatory to the impulse circuit when the induced electromotive force is opposite in phase to the oscillatory current is small compared with the energy transferred from the impulse to the oscillatory circuit when the induced electromotive force is in phase with the oscillatory 90 current. When triggering takes place, as indicated in Fig. 2, there is an initial transfer of some energy from the oscillatory circuit 1 to the impulse circuit 6 in order to assist in breaking down the discharge gap. 95 This energy is, however, immediately retransferred back to the oscillatory circuit as soon as the induced electromotive force comes into phase with the oscillatory current. 100

The exciting impulses are extinguished so quickly that the train of oscillations excited in the oscillatory circuit is a single period train of free oscillations, and thus the double period oscillations which are produced by 105 current oscillations in two coupled oscillatory circuits and radiated as a double period wave train by the antenna, are not produced in the present apparatus.

Under the best conditions of operation 110 the current impulses in the circuit 6 are apparently uni-directional, being extinguished before a reverse flow of current can take place across the discharge gap. Under some conditions apparently a slight reverse current succeeds the main or uni-directional wave, but is inconsequential as far as the operation of the apparatus is concerned. Substantially the entire energy transfer 115 from the impulse to the oscillatory circuit takes place during a single current impulse or wave, and this wave has a duration considerably longer than the single waves or alternations of the oscillatory current which it excites. In this respect the present apparatus differs from the usual quenched gap type of apparatus in which a number of current waves take place in the exciting circuit and the current waves are of substantially the same wave length as the oscil- 125 130

lations which they excite. By virtue of this fact, a condition of practically pure impact excitation results in the present apparatus.

The present apparatus also differs from the usual wireless apparatus, in that instead of having two circuits tuned or in resonance, the impulse circuit 6 of the present apparatus is decidedly out of tune with the oscillatory circuit 1, so that no resonance can take place between them.

Still another distinction between the present apparatus and that of the usual construction resides in the fact that the coupling between the impulse and oscillatory circuits 6 and 1 respectively is much closer than that hitherto usual in commercial apparatus.

The present apparatus is particularly designed to operate under the heavy currents necessary for commercial wireless transmitting stations. One feature which apparently is of great importance in making the present apparatus capable of commercial use is a spark gap which is able to carry heavy currents. In the present apparatus the spark gap is composed of two relatively moving good heat conducting metallic surfaces, in which the arc is prevented from continuing at any one place and in which the arc-heated surfaces are separated, and fresh and comparatively cool surfaces are continuously presented for subsequent discharges. It has been found that stationary gaps of the so called rectifying type, while operating under some particularly favorable conditions to permit unidirectional condenser discharges, are unsuited for commercial apparatus because they are incapable of operating under the necessary amounts of current. Apparently the discharge gap having relatively moving good heat conducting metallic surfaces in combination with close coupling between the impulse and oscillatory circuits is necessary to render the apparatus capable of substantially pure impact excitation as hereinbefore described.

While I have explained the theory of the operation of the apparatus in some detail as it is at present understood by me, the invention resides in the apparatus and not in the theory, and in stating the probable theory it is not my intention to limit myself to such theory but rather to state it as the probable explanation of the operation of my apparatus.

The present invention is not limited to the illustrated embodiment, but may be embodied in other constructions within the scope of the following claims.

I claim—

1. An apparatus for producing electrical oscillations having, in combination, an oscillatory circuit, an impulse circuit coupled with the oscillatory circuit, the coefficient of coupling between the two circuits being

greater than fifty per cent., said impulse circuit including a condenser and a discharge gap comprising two relatively rotating sectored parallel metallic plates, and a feeder circuit for charging the condenser. 70

2. Apparatus for producing electrical oscillations having, in combination, an oscillatory circuit in which the oscillations are produced, an impulse circuit coupled with the oscillation circuit including a condenser 75 and a discharge gap comprising two relatively moving good heat conducting surfaces, and a feeder circuit for charging the condenser at such a rate that the condenser discharges in the impulse circuit will occur before the previously excited trains of oscillations in the oscillatory circuit dies down, said oscillations in the oscillatory circuit reacting on the impulse circuit and serving to trigger off the condenser discharges in a predetermined phase relation with the oscillations so as to reinforce and sustain the declining oscillations. 80

3. Apparatus for producing electrical oscillations having, in combination, an oscillatory circuit, and means for producing oscillations in the oscillatory circuit by impact excitation comprising an impulse circuit closely coupled with the oscillation circuit and including a condenser and a discharge gap having two relatively moving good heat conducting metallic surfaces, said spark gap in conjunction with the transfer of energy from the impulse circuit to the oscillatory circuit, due to the close coupling, 90 serving to cause a substantially non-oscillatory condenser discharge in the impulse circuit, and a feeder circuit for charging the condenser. 95

4. An apparatus for producing electrical oscillations having, in combination, an oscillatory circuit, an impulse circuit coupled with the oscillatory circuit, the co-efficient of coupling between the two circuits being greater than fifty per cent., said impulse circuit including a condenser and a discharge gap comprising two relatively moving good heat conducting metallic surfaces, and a feeder circuit for charging the condenser. 105

5. Apparatus for producing electrical oscillations having, in combination, an oscillatory circuit, and means for producing oscillations therein by impact excitation comprising an impulse circuit closely 110 coupled with the oscillatory circuit and including a condenser and a discharge gap having relatively moving good heat conducting metallic surfaces, said impulse circuit having a natural time period of at least considerably greater than the natural time period of the oscillatory circuit, said discharge gap taken in conjunction with the transfer of energy from the impulse circuit due to the close coupling between them, 115 120 125 130

serving to cause a substantially non-oscillatory condenser discharge of a duration greater than one-half the time of a complete current oscillation in the oscillatory circuit, and a feeder circuit for charging the condenser.

6. Apparatus for producing electrical oscillations having, in combination, an oscillatory circuit, and means for producing sustained oscillations in the oscillatory circuit comprising an impulse circuit closely coupled with the oscillatory circuit and including a condenser and a discharge gap having two relatively moving good heat conducting surfaces, and a feeder circuit for charging the condenser at such a rate that the condenser discharges in the impulse circuit will occur before the previously excited trains of oscillations in the oscillatory circuit die down, said oscillations in the oscillatory circuit reacting on the impulse circuit and serving to trigger off the condenser discharges at a predetermined phase relation with the oscillations so as to reinforce and sustain the declining oscillations.

7. Apparatus for producing electrical oscillations having, in combination, an oscillatory circuit, and means for producing sustained oscillations therein by impact excitation comprising an impulse circuit closely coupled with the oscillatory circuit and including a condenser and a discharge gap having relatively moving good heat conducting metallic surfaces, said impulse circuit having a natural time period considerably greater than the natural time period of the oscillatory circuit, and a feeder circuit for charging the condenser at such a rate that the condenser discharges in the impulse circuit will occur before the previously excited trains of oscillations in the oscillatory circuit die down, said oscillations in the oscillatory circuit reacting on the impulse circuit and serving to trigger off the condenser discharges in a predetermined phase relation with the oscillations so as to reinforce and sustain the declining oscillations.

8. Apparatus for producing electrical oscillations having, in combination, an oscillatory circuit, and means for producing sustained oscillations therein by impact excitation comprising an impulse circuit closely coupled with the oscillatory circuit and including a condenser and a discharge gap having relatively moving good heat conducting metallic surfaces, said impulse circuit having a natural time period at least one-half greater than the natural time period of the oscillatory circuit, said discharge gap taken in conjunction with the transfer of energy from the impulse to the oscillatory

circuit due to the close coupling between them, serving to cause a substantially non-oscillatory condenser discharge in the impulse circuit of a duration greater than one-half of the time of a complete current oscillation in the oscillatory circuit, and a feeder circuit for charging the condenser at such a rate that the condenser discharges in the impulse circuit will occur before the previously excited trains of oscillations in the oscillatory circuit die down, said oscillations in the oscillatory circuit reacting on the impulse circuit and serving to trigger off the condenser discharges in a predetermined phase relation with the oscillations so as to reinforce and sustain the declining oscillations.

9. Apparatus for producing electrical oscillations having, in combination, an oscillatory circuit, an impulse circuit closely coupled with the oscillatory circuit and including a condenser and a sectored rotary discharge gap, a feeder circuit for charging the condenser at such a rate that a number of condenser discharges occur upon each coincidence of the gap sectors, and a reservoir circuit shunted across the condenser and including inductance and capacity so proportioned that the reservoir circuit has approximately the same natural frequency as the frequency of coincidence of the sectors of the gap.

10. Apparatus for producing electrical oscillations having, in combination, an oscillatory circuit, an impulse circuit closely coupled with the oscillatory circuit and including a condenser and a discharge gap having provision for dividing the condenser discharges into groups having an audible group frequency, a feeder circuit for charging the condenser, and a reservoir circuit shunted around the condenser including capacity and inductance so proportioned that the reservoir circuit has a natural frequency approximately that of the group frequency.

11. Apparatus for producing electrical oscillations having, in combination, a circuit including a condenser and a discharge gap having provision for dividing the condenser discharges into groups of audible frequency, a feeder circuit for charging the condenser, and a reservoir circuit shunted around the condenser including inductance and capacity so proportioned that it has a natural frequency approximately that of the group frequency.
